(57) **CLAIM**

The ornamental design for auxiliary grip for a golf club, as shown and described.

DESCRIPTION

FIG. 1 is a right side elevational view of an auxiliary grip for a golf club according to the invention;

FIG. 2 is a left side elevational view thereof;

FIG. 3 is a rear elevational view thereof;

FIG. 4 is a front elevational view thereof;

FIG. 5 is a top plan view thereof;

FIG. 6 is a cross-sectional view thereof taken along the line 6—6 in FIG. 5;

FIG. 7 is a bottom plan view thereof; and,

FIG. 8 is a right side elevational view thereof, wherein the broken line depictions and surface treatment of a golf club are illustrative of environmental structure and form no part of the claimed design.
